A. D. DAVID

METHOD AND APPARATUS FOR TREATING PETROLEUM OIL

Filed Feb. 14, 1923

UNITED STATES PATENT OFFICE.

AUBREY D. DAVID, OF CHICAGO, ILLINOIS, ASSIGNOR TO THE UNIVERSAL OIL PRODUCTS COMPANY, OF CHICAGO, ILLINOIS, A CORPORATION OF SOUTH DAKOTA.

METHOD AND APPARATUS FOR TREATING PETROLEUM OIL.

Application filed February 14, 1923. Serial No. 619,036.

This invention relates to improvements in a method and apparatus for treating petroleum oil, and refers more particularly to an apparatus used in connection with the pressure distillation of petroleum oils for producing relatively light oils such as gasoline.

Among the objects of the invention are to provide a method and apparatus which provides a safer means for isolating the expansion chambers, in order that they may be cleaned while the rest of the apparatus is kept in operation.

The single figure is a diagrammatic side elevational view of the apparatus.

Referring to the drawings: 1 is a furnace in which is mounted a heating coil 2. Oil is supplied to the heating coil from any convenient source through a charging line 3 controlled by a valve 4. The heating coil 20 is connected by transfer line 5 and header 6 to vaporizing chambers 7 and 8. These chambers communicate through vapor lines 9 and 10 to a common line 11, which leads to a dephlegmator 12. The dephlegmator 25 in turn is connected by pipe 13 to condenser 14 mounted in condenser box 15. The discharge end of the condenser coil 14 is connected by a pipe 16 to a receiving tank 17 which is equipped with a pressure release 30 pipe 18, pressure gauge 19, liquid level gauge 20, and liquid draw-off valve 21.

The oil to be treated is introduced, as explained, and raised to a conversion temperature in the heating coil, after which it is directed through the transfer pipe 5, and into either of the expansion chambers 7 or 8 by manipulation of valves 22, 23, 24 and 25. If it is desired to introduce the heated oil into the expansion chamber 7, the valves 40 22 and 23 are opened and the valves 24 and 25 are closed. Under these conditions the heated oil will collect in the chamber 7, where the evolved vapors will rise through the vapor line 9, and pass to the dephlegmator through the line 11. The unvaporized liquid oil constituents may be drawn off intermittently or continuously from the chamber 7 through the draw-off lines 26, controlled by valves 27.

When the carbon accumulation has become objectionable in the chamber 7, this chamber may be cut out of the system by closing the valves 22 and 23 in the header 6 and valve 28 in the vapor line 9. This chamber is then isolated from the system, and after re-

moving the upper and lower manhole plates, it may be cleaned of the accumulated residual carbonaceous material.

Prior to cutting out the chamber 7, the chamber 8 is cut into the system by opening the valve 24 and 25 in the header 6 and the valve 29 in the vapor line 10. While the chamber 7 is cut out of the system, the chamber 8 will be utilized as an expansion or vaporizing zone.

The chamber 8 is equipped with liquid draw-off lines 26 controlled by valves 27 similar to the residual draw-off lines in the chamber 7. The vapors during operation are passed from the chamber that is being used through the vapor lines to the dephlegmating stage, and after being refluxed are finally condensed and collected as liquid residue in the receiving tank 17.

During the period of time that either chamber is cut out of the system, it is desirable to prevent any casualty to operators cleaning the tanks, due to the failure of one of the valves in the header 6. For this reason a cool liquid medium such as cool oil 80 is pumped from any convenient source such as a tank, 30, and is charged by means of the pump 31 through a line 32, which is connected to separate lines 33 and 34 communicating with portions of the header 6 interposed between the valves 24 and 25 and the valves 22 and 23, respectively the oil being returned to the tank 30 through the lines 37 and 40. In the event that the chamber 8 is cut out of the system, the cool oil will be 90 circulated through the pipe 32 and 33 into the portion of the header 6 between the valves 24 and 25. At this time it is essential that the valve 35 in the line 34 be closed and the valve 36 in the line 33 be open. This 95 will maintain a head of oil in the portion of the header 6 between the two valves 24 and 25 so that should the valves fail, the hot oil coming from the heating tubes will be immediately tempered prior to its introduction to the chamber 8 by cold oil introduced from the tank 30. Also a counter pressure substantially equal to the pressure on the hot oil may be maintained upon the cooling medium to counteract the pressure 100 on the hot oil, so that the failure of the valve is practically an impossibility.

The cooling medium charged through the line 36 is withdrawn from the header through the line 37 controlled by a valve 38, 110

thus the cooling medium is circulated to the header and from the header back to the tank in a continuous circuit. During its circulation, in addition to the valve 35 being closed, 5 it is also necessary that the valve 39 in the discharge line 40 be also closed.

When the tank 8 is cut back into the system and the tank 7 is cut out for cleaning, the circulation of the cooling medium will be 10 transferred from that portion of the header between the valves 24 and 25 to the section of the header between the valves 22 and 23. This is effected by closing valves 36 and 38 and directing the cool oil through the lines 15 34 and 40 by opening the valves 35 and 39. It is obvious that circulation will then take place through the header communicating with the chamber 7 in place of the circulation of cool oil through that portion of the 20 header communicating with the chamber 8.

By circulating cool oil in this manner at sufficient pressure, the cleaning of the chambers during operation of the remaining part of the apparatus may be made comparatively safe.

I claim:

1. In an apparatus for treating oil, the combination with means for heating the oil of alternate vaporizing means, separate 30 transfer and vapor lines connected thereto, means interposed in the transfer and vapor lines for isolating either of the vaporizing means from the system, means for introducing a cooling medium into either of the 35 transfer lines communicating with an isolated vaporizing means during the period it is cut out of the system.

2. In an apparatus for treating oil, the combination with means for heating the oil 40 of alternate vaporizing means, transfer lines communicating between the heating and vaporizing means, vapor lines connected to the vaporizing means, means interposed in the transfer and vapor lines for isolating 45 either of the vaporizing means from the system, means for introducing into and circulating a cooling medium through a localized portion of the transfer line communicating with the isolated vaporizing means during 50 the period it is cut out of the system.

3. In an apparatus for treating oil, the combination with means for heating the oil, of alternate vaporizing means, transfer and vapor lines connected to the vaporizing

means, means interposed in the transfer and 55 vapor lines for isolating either of the vaporizing means, means for introducing into and circulating a cooling medium at a pressure substantially that of the oil in the system through a portion of the transfer line communicating with the vaporizing means cut 60 out of the system.

4. In an apparatus for treating oil, the combination with means for heating the oil of alternate reaction zones, transfer means 65 for selectively passing heated oil from the heating means to either of said reaction zones, means for isolating either one of said reaction zones from the remaining apparatus, means for circulating a pressure 70 balancing medium at a pressure substantially equal to the pressure maintained on the oil undergoing treatment in the apparatus through the transfer means communicating with the reaction zone, which is isolated from the remaining portion of the apparatus to prevent leakage of hot oil from the 75 remaining portion of the apparatus into the isolated reaction zone.

5. The method of isolating either one of alternate reaction zones of an oil cracking apparatus, which consists in discontinuing the supply of oil to the zone to be isolated, in simultaneously admitting oil to the other of the alternate reaction zones, in thereafter balancing the pressure between the reaction zones and preventing the leakage of hot oil into the zone to which the supply of oil has been discontinued by introducing a pressure balancing medium into a portion of the 80 apparatus intermediate said alternate zones.

6. The method of isolating either one of alternate reaction zones of an oil cracking apparatus, which consists in discontinuing the supply of oil to the zone to be isolated, in simultaneously admitting oil to the other of the alternate reaction zones, in thereafter 95 balancing the pressure between the reaction zones and preventing the leakage of hot oil into the zone to which the supply of oil has been discontinued by circulating a cooling medium, under a pressure substantially equal to the pressure maintained in the reaction zone to which oil is being supplied, through 100 a portion of the apparatus intermediate said alternate reaction zones.

AUBREY D. DAVID.
